UNITED STATES PATENT OFFICE

2,132,571

TIE-PLATE CONSTRUCTION

Thomas Maney, Louisville, Ky.

Application July 27, 1931, Serial No. 556,206

2 Claims. (Cl. 238—304)

My present invention relates to an improvement in tie-plate construction for use between main rails and ties, and relates particularly to the manner of adjustably securing the rail to the tie, being an improvement on my former Patents Nos. 1,067,124 and 1,067,125, of July 8, 1913, and 1,474,276, of November 13, 1923.

My present invention differs from those constructions in its organization, although embodying some of the features of said patents in a different combination, and with easily recognized improved results.

This invention embodies the following novel features, to wit:

(1) Provision for direct lateral adjustment of the rail on the plate, thereby permitting the use of various rail sections by the inexpensive use of lateral adjustment pieces, selected and placed according to the relative position of the rail-base and tie-plate, the latter provided with punchings just within the shoulders on the tie-plate and adapted to receive adjusting assembly pieces, which are fitted to the punchings in the tie-plate and approximately fill the spaces between the rail-base and shoulders of the tie-plate to afford lateral support for, and prevent sidewise movement of, the rail.

(2) The compensating feature, resulting from the slope on the bottom of the inner end of the tie-plate, causing the adjusting cant of the latter to be inwardly and within controlled limits in connection with a main rail, clip adjusting pieces, a screw extending into the tie through a hole of greater diameter than the greatest diameter of the screw, a spring-clip through which the screw extends resting at one end upon the rail-base, and at the other end upon the outer end of the tie-plate, and a nut for turning on a threaded portion of the screw and against the spring-clip for applying the required tension directly upon the spring-clip, and thereby curtailing the vertical movement of the tie, due to wave motion of the rail, and rendering impossible any movement between the plate and the tie.

(3) A screw-spike adapted to extend through a hole in the tie-plate of greater diameter than any part of the screw-spike above the tie-plate, with separable screw-nut head.

(4) A resilient steel spring holding down clip in combination with tie-plate, rail, and screw-spike adapted to extend through the tie-plate and tie without directly and rigidly holding the tie-plate down upon the tie.

In the accompanying drawings:

Fig. 1 is a transverse section through the assembled parts;

Fig. 2 is a top plan view thereof;

Fig. 3 is a sectional view showing a slight modification;

Figs. 4, 5, 6 and 7 are perspective views and end elevations of the adjusting pieces;

Fig. 8 is a perspective view of one of the adjusting pieces of the type shown in Fig. 3; and

Fig. 9 is a side elevation showing coil springs 10 on the tie-plate spikes.

The numeral 1 refers to a main rail, which is seated upon a tie-plate 2 secured to a cross-tie 3 by screw-spikes 4 or other forms of spikes, to hold the tie-plate in place. The under face 15 of the tie-plate 2 is provided with pendant ribs 5, which afford the main hold against lateral movement of the tie-plate on the tie 3.

The tie-plate 2 is provided with holes 6 therein for receiving intermediate screw-spikes 7, 20 each of which is provided with an enlarged intermediate portion 8 normally disposed within the holes 6, and above this intermediate portion 8 is a threaded portion 9 terminating at its upper end in a squared portion 10, adapted to receive 25 a wrench or the like for turning the spike. The holes 6 in the tie-plate, through which the spikes project, are larger in size than any portion of the spikes, so that the tie-plates may be readily removed from over the spikes without removing the latter from the ties.

This relationship between the tie-plate and spike 7 is also true of the spikes 4. Nuts 11 are threaded onto the threaded portions 9 of the spikes and form the adjustable heads therefor. 35 The removal of these nuts permits the tie-plate and its associate parts to be removed from the tie.

I have found by experience that a great objection to the screw-spike is that initially great 40 power is required to put them down, and being firmly embedded in the tie without movement or vibration, the acid of the wood causes them to corrode and become cemented to the wood. This would be an advantage if the spike did not have 45 to be turned again for readjustment, but readjustment is necessary and consequently difficult.

The repeated breaking of the bond causes injury to both the spike and the tie. By making the spike smaller in size than the hole through 50 the tie plate, and with a separable screw-head, the advantage of the firm bond is obtained without injury due to displacement, and adjustment may be readily made or the plate entirely removed by running off the nuts.

55

At the same time, there is nothing to prevent the tie-plate from being adjusted solidly down on the tie, for the holes through the tie-plate are larger than the largest portion of the screw-spike, making it unnecessary to turn the spike in order to adjustably secure the tie-plate in place.

Spring-clips 12 have their intermediate portions arranged beneath the nuts 11, and their outer ends are curved to engage on the inner sides of flanges 13, while their inner ends bear upon the base flanges of the main rail 1, as illustrated in my former Patent No. 1,067,125, of July 8, 1913.

Shoulders 14 and 15 are formed on the upper surface of the tie-plate 2 and of sufficient distance apart to receive the base of the main rail 1 therebetween, with the edges of the base flanges spaced from these shoulders. The tie-plate 2 is provided with slots 16 and 17 at the inner sides of the shoulders and projecting sufficiently far inward to normally underlie the edges of the base flanges of the main rail.

Adjusting-pieces 18 and 19 are provided between the edges of the main rail base flanges and the shoulders 14 and 15. These adjusting-pieces are preferably castings of the construction such as is shown in Figs. 4 to 7. The adjusting-piece 18 is provided with a depending portion 20, and a forward arm 21, both adapted to be seated within the slot 16 with the arm 21 engaging under the base flange of the main rail, as shown in Fig. 1. The adjusting-piece 19 is provided with a depending portion 22 and a forwardly extending arm 23, both of which are adapted to be seated in the slot 17 with the arm 23 projecting under the base flange of the main rail.

A notch 24 is provided in the back side of the depending portion 22, to receive the arm 21 of the adjusting-piece 18 when it is desired to place both adjusting-pieces on one side of the rail. The provision of these adjusting-pieces 18 and 19 interposed between the shoulders 14 and 15 and the base flange of the rail gives wide and variable lateral adjustment of the rail without disturbing the seat of the plate upon the tie, and are formed so as to be absolutely secure in place.

If desired, one of the adjusting-pieces 18 or 19, as for instance the piece 18, may be removed and replaced by one or more shims 25, as shown in Fig. 3.

My present tie-plate is adapted primarily to receive and support a main rail only, whereas in my former Patent No. 1,474,276, of November 13, 1923, the tie-plate was shown as applied to the supporting of a main rail and a guard rail.

In my present invention, the underside of the tie-plate normally has its major portion seated upon the tie and is provided with an inclined inner portion 26, as shown in Figs. 1 and 3, and which inclined portion extends at an obtuse angle

to the major portion of the bottom surface of the tie-plate.

If the tie plates are used on a straight track or track having very little curvature, the parts would be disposed in the full-line positions of Fig. 1. This approximately balances the plate, but the exact balance for the exact resultant arising will be automatically found when the plate gains the slight inward cant necessary to prolong the inside bearing area and make it equal to that outside of the resultant. On the other hand, if plates are to be used on high curvatures, the rail will be adjusted to the dotted-line position of Fig. 1, in which one of its flanges bears against the shoulder 15 and the adjusting-pieces 18 and 19 or similar adjusting-pieces are both placed in the slot 16 to hold the opposite base flange of the rail in place. This adjustment of the rail cooperating with the inclined portion 26 of the lower face of the tie-plate causes the plate to find its exact balance automatically as before.

The adjusting-pieces 18 and 19 are interchangeable according to the curve of the rails, or may have suitable shims substituted therefor, or they may both be placed on one side, but one or more of these adjusting-pieces has an arm projecting under the base flange of the rail.

The spikes 4 have coil springs 27 interposed between the tie-plate 2 and nuts 11' threaded onto these spikes, as shown in Fig. 9.

I claim:

1. In railway construction, the combination of a tie-plate adapted to receive a rail, means for fastening the tie-plate to a tie, said tie-plate having a flat lower portion normally seated on a tie, and an inclined portion at one end of the tie-plate initially removed from the tie, the rail being adjustable toward the inclined portion to different lateral positions on the tie plate, means for engaging the rail in its laterally adjusted positions to hold the same in place, and one or more adjusting-pieces interposed between the tie-plate and rail in its different adjusted positions, said adjusting-pieces being spaced inside the tie-plate fastening means and held in place only by the tie-plate and rail.

2. In railway construction, the combination of a tie-plate and rail, the major portion of the lower surface of the tie-plate being flat, and one portion at an end of the tie-plate being inclined, whereby said portion is initially removed from the tie, the rail being adjustable toward the inclined portion, said inclined portion having holes therethrough, means extending through the holes for securing the tie-plate to the tie, and means spaced inside of said securing means for securing the rail in different laterally adjusted positions on the tie-plate and being held in place only by the tie-plate and rail.

THOMAS MANEY.
